(57) **CLAIM**

The ornamental design for an end portion of a tape measure, as shown and described.

DESCRIPTION

FIG. 1 is a perspective view of an end portion of a tape measure showing my new design;

FIG. 2 is a front view thereof;

FIG. 3 is a bottom view thereof;

FIG. 4 is a left side view thereof; and,

FIG. 5 is a bottom perspective view thereof.

The broken lines are environmental and form no part of the claimed design. The claimed end portion of a tape measure includes ferromagnetic material as indicated by the stippling in FIGS. 1, 2 and 5. The particular shape of the ferromagnetic material, however, forms no part of the claimed design.
